UNITED STATES PATENT OFFICE.

ANGUS S. MACDONALD, OF GREAT NECK, NEW YORK, ASSIGNOR TO SNEAD & COMPANY, A CORPORATION OF NEW JERSEY.

FLOOR GRID.

Application filed July 1, 1924. Serial No. 723,440.

This invention relates to metallic floor grids for taking up wear on asphalt or concrete floors subject to heavy traffic or hard usage.

One of the primary objects of my invention is to provide a grid which is adapted to interlock with adjacent similar grids when the filling material is applied.

Another object of my invention is to provide a counterpart grid which when a multiplicity thereof are assembled and filling material applied will expose a metallic wearing surface of uniform design.

Still another object of my invention is to provide a grid which when filled with floor material will prevent cupping out of the filling material with wear.

Still another object of my invention is to provide a cast grid in which the draft allowance slopes in such manner to anchor the grid securely when the filling material is applied.

Still another object of my invention is to provide a grid in which every portion is tied together thus producing a rigidly constructed grid.

Still another object of my invention is to provide a grid which can be easily leveled when surfacing a rough floor.

A more specific object of my invention is to provide a grid in which the main walls are of uniform depth and consequently of uniform strength.

How these and various other objects and advantages can be realized through my invention will appear from my description hereinafter of the best construction for the purpose known to me.

In the drawings, Fig. 1 is a plan view of a complete grid.

Fig. 2 is a section taken on line 2—2 of Fig. 1 with a fragment of the left and right adjacent grids in assembled position.

Fig. 3 is a section taken on line 3—3 of Fig. 1.

Fig. 4 is a section taken on line 4—4 of Fig. 1 with a fragment of its adjacent grids in assembled position.

Fig. 5 is a fragmentary plan view showing how adjacent grids overlap at the corners to produce a uniform design.

Fig. 6 is a fragmentary plan view of a completed portion of the floor, and

Fig. 7 is a fragmentary section at a point

where adjacent grids meet showing a feature of my invention for locating the grids.

The preferred form of grid illustrated is a metal casting, the main portion thereof being comprised of a plurality of intersecting bars 1 and 2, which form the pockets A for receiving a mastic or filling material such as asphalt or concrete for instance. Intermediate the points of intersection I have provided the fingers 3 extending into and terminating short of the center of the pockets thus reducing the unprotected surface included in the large squares and affording a large area of metal protection with a minimum quantity of metal. Similar fingers 3^a extend outwardly from the edge portions 4 and 5.

The contiguous edge portions 4 and 5 are constructed to overhang and the two edges 6 and 7 opposite thereto are constructed to underhang. By this construction the grids are adapted to be used as complements in covering a large area. The underhung portions 6 and 7 are provided with half pockets B, and are cut down in height so as to be substantially one half the height of the main pockets A, with the exception of the end fingers 6^a which are of the same height as the intersecting bars. Thus it will be seen in assembling a series of grids that these underhung portions can slip under the overhung portions of the next adjacent sections, which portions are cut down in depth in an amount to allow this to be done. When thus assembled, the side or end walls 8 of the portions 4 and 5 overlie the inside walls 9 of the portions 6 and 7, and the fingers 3^b and bars 1^a and 2^a overlie the outside walls 10 and bars 1^b and 2^b thereof, thus forming superimposed pockets which when filled with mastic will become securely interlocked, and at the same time will present a uniform design of the exposed metal work.

To maintain this uniformity of design with various arrangements I have cut away the corners at 11, 12 and 13 so that the corners which come together will form complete squares. In order to simplify the location of the grids when assembling a series thereof I have provided depressions or notches 8^a in the side or end walls 8 into which the end portions 8^b of the intersecting bars 1 and 2 fit. These depressions not only serve to locate adjacent grids but also serve to reduce to a

minimum the clearance between the top portions of the bars where two grids meet.

As the grids are cast and used without any machining it is necessary to provide

5 clearance between the lower surface of the overhang of one grid and the upper surface of the underhang of its adjacent grid, in order to prevent these surfaces from coming in contact and causing the grids to rock

10 on account of irregularities in the casting or in the rough floor or setting. This clearance is indicated in Figs. 2 and 4.

It is to be noted that this gap is so slight that there is a possibility that the filling 15 material would not flow therein, thus leaving the overhung portion unsupported and creating a weakness. In order to overcome this disadvantage I have made the walls 8 of the overhanging portions 4 and 5 of the 20 grids which overlie the walls 9 of the underhanging portions 6 and 7 of adjacent grids, so that they do not exactly line up vertically with the walls 9 which causes overlap at 14, see Figs. 2 and 4. Hence the filling material when applied forms a support under the overlap of the walls, insuring adequate support at these points.

By making the casting so that the parting line falls intermediate the upper and lower 30 surfaces of the grid, causing the draft to slope both ways therefrom I insure a secure anchor for the grid when the filling material is applied, and at the same time a casting which is simple to manufacture.

35 At intersections of the bars 1 and 2 the bosses 15 are provided to facilitate setting of the grids on rough floors. Using these bosses enables me to make the main walls of the grid of uniform depth and strength.

40 It is to be understood that in order to have a maximum wearing surface with a minimum amount of material I may construct the fingers 3 to extend only above the substantial center line of the main walls.

45 By choosing the kind of metal of which the grids are made and the kind of mastic into which they are bedded a floor can be built up that may be, acid, heat, or wear resisting or all of them together.

50 I claim:

1. A floor grid having edge pockets so constructed that when a plurality of grids are assembled the pockets of one edge of a grid are superimposed over edge pockets of 55 the adjacent grid and interlocked when the floor material is applied.

2. A grid having underhung and overhung edge portions whereby when a plurality of grids are assembled the overhung

60 portions of one grid overlie the underhung

portions of an adjacent grid, said portions being so disposed with respect to one another that the overhung portions are supported by the filling material.

3. A floor grid comprised of intersecting 65 bars providing pockets, each bar being provided with oppositely projecting fingers extending into the pockets located on either side of said bar.

4. A floor grid comprised of intersecting 70 bars providing pockets, each bar being provided with fingers extending into the pocket but terminating short of the center thereof.

5. A floor grid comprised of intersecting 75 bars providing pockets, and leveling bosses extending downward from the intersecting bars.

6. In combination, a pair of floor grid sections arranged for assembly together and each comprising a plurality of intersecting 80 bars, the meeting edge of one of said grid sections being characterized by the provision of a longitudinally extending bar formed with a plurality of spaced notches for receiving the adjoining ends of the transversely extending bars of the other of said sections.

7. A floor grid composed of intersecting 85 bars and having contiguous edge portions provided with a plurality of notches opposite the termini of said bars, said notches extending substantially transversely of the plane of the grid and adapted to receive bars of adjacent grids whereby a uniform 90 floor design will be formed when a plurality of grids are assembled.

8. A floor grid composed of intersecting 95 bars forming pockets, and fingers extending laterally from said bars, two contiguous edge bars of said grid having notches between the fingers extending substantially transversely of the plane of the grid and adapted to engage bars of adjacent grids to align the grids laterally when a plurality 100 thereof are assembled.

9. A floor grid composed of intersecting 105 bars and having an overhung edge portion and an underhung edge portion with notches in one of said portions, said portions being adapted to cooperate with complementary parts of adjacent grids for vertical alignment of said grids and for interlocking of the grids by means of the floor material, and said notches being adapted to engage bars of adjacent grids for horizontal alignment 110 of the grids.

In testimony whereof, I have hereunto signed my name.

ANGUS S. MACDONALD.
